UNITED STATES PATENT OFFICE.

WILLIAM W. HILDRETH, OF ANGOLA, INDIANA.

WINDMILL.

SPECIFICATION forming part of Letters Patent No. 247,914, dated October 4, 1881.

Application filed July 1, 1881. (Model.)

To all whom it may concern:

Be it known that I, WILLIAM W. HILDRETH, a citizen of the United States of America, residing at Angola, in the county of Steuben and State of Indiana, have invented certain new and useful Improvements in Windmills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to an improvement in windmills; and it consists in the peculiar construction of parts, whereby a cheap, simple, and effective windmill is produced, as will be more fully described hereinafter.

The accompanying drawings illustrate my invention.

Figure 1 is side elevation of my invention. Fig. 2 is a cross-section on the line *x x*, Fig. 1. Fig. 3 is an enlarged sectional view on the line *z z*, Fig. 2. Fig. 4 is a section of the cross-head on the line *y y*, Fig. 3. Figs. 5 and 6 are detailed views of the vane coupling devices. Fig. 7 is a plan view of the centering device, showing the pipe and piston of the mill in section.

A represents the tower of the mill, to the top of which is fixed the cap *B*. Through a hole in this cap extends the hollow cylinder or pipe *a*, which is free to turn, and forms the main support of the operating parts of the mill. To the top of the pipe *a* is rigidly secured the casting *b*, which is round in cross-section, and has the two uprights *b'*, the open spaces *b²*, and top *b³*, and bottom *b⁴*. Through the center of the top is made the hole *b⁵*, and into this hole is set the bushing *c* for the reception of the upper end of the bracket *d*, shaped as shown in Fig. 1, the lower end of which bracket is made with an annular foot-piece, *d'*, which encircles the pipe *a* immediately beneath the bottom of the casting *b*. By this construction the bracket *d* is left free to turn, being pivoted in the bushing at the top and upon the pipe *a* at the bottom of the casting *b*. The lower portion of the bracket-arm *d* is bent at *d²*, as shown in Fig. 3, so as to turn slightly away from the center of the cylinder *a* and through

the bent-out portion of the bracket, extends the bearing *d³* for the shaft *e*. Just below the bearing *d³* to the bracket is attached a strap or band, *f*, which encircles the casting *b*, the said band *f* being provided with the stops *f'* and *f²*. Rigidly secured to the casting *b* at the opposite side to that from which extends the bracket *d*, is a second bracket, *g*, shaped as shown in Fig. 1, the lower end of which curves inward, and is provided with a circular foot-piece at *g'*, which encircles the cylinder *a* immediately below the foot *d'* of the bracket *d*, filling the space between the foot of the bracket *d'* and the top of the cap-piece *B*, as shown.

It will be readily seen that the brackets *d* and *g* can be turned through a quarter of a circle independently of each other, this movement being limited by the stops *f'* and *f²*, as shown in Fig. 2. I also provide the frame *b* with the stops *b⁶*, one of which is brought in contact with one of the projections *d⁴* with which the shaft-bearing is provided when the wheel is thrown out of the wind.

To the inner end of the shaft *e* is secured the wheel or crank *h*, which is placed a little to one side of the center of the cylinder-support, as before described, and in this wheel is pivoted the wrist-pin *i*, which has a screw-thread on its outer end and is provided with a nut, *k*, for tightening it, to compensate for the wear. From the inner face of the wheel *h* the pin is made square, the square portion fitting into a slot, *l*, made in the cross-head *m*, with which the pump or other mechanism actuating rod *n* is provided. This pump end passes through the cylinder *a*, the upper ends being held in the guides *o*, secured to the upper end of the bracket-arm *d*. It will be readily seen that as the wheel revolves the wrist-pin will travel from end to end in the slot *l*, thus giving the vertical reciprocating motion to the pump end without the aid of a connecting-rod, as usually employed. By the use of this device the side strain on the pump end occasioned by the connecting-rod arrangement is avoided, and the motion of the rod is made positive and direct, without a tendency to force the rod to either side of its center, thus making the motion of the machine more regular and perfect, and saving the power lost on the bending strain which is usually im-

parted to the pump-rod. By pivoting the wrist-pin in the wheel and having the portion which enters the slot in the cross head square the friction of the pin is greatly reduced, the rotary grinding motion which would result were the wrist-pin round and rigidly fixed to the crank-wheel being avoided.

In the inner end of the wrist-pin is made a screw-threaded recess for the reception of the screw *p*, which presses the washer *q* against the inner face of the cross-head, as shown in Fig. 4. By this arrangement of devices the screw may be tightened to compensate for wear on the inner face of the cross-head.

The outer end of the shaft *e* carries the wind-wheel *D*, which may be of any desired construction. From the rear of the bracket *g* extends the vane or rudder *E*, for keeping the wheel before the wind.

In order to enable the wheel to be turned out of the wind when it is desired to stop it the top of the end of the bracket *g* is provided with a transverse bearing, *r*, through which extends the rock-shaft *s*, one end of which is fastened to the lever *t*, which extends parallel with the vane and has one of its ends provided with a weight, *u*, the other end receiving a cord, *v*, which extends to the ground. To the opposite end of the rock-shaft is fixed the arm *w*, from the lower end of which extends the connecting-rod *w'*, which connects it to the bracket *d*, as shown in Figs. 1 and 2. By pulling the string *v* the weighted lever *t* will partially rotate the rock-shaft *s*, which will give motion to the arm *w*, and through it to the connecting-rod *w'*, by which means the bracket *d*, carrying the wind-wheel, will be turned through a quarter of a circle and the wheel stopped. By releasing the cord the weighted lever will turn the wheel back to the original position, when it will be again acted upon by the wind.

In setting up a windmill it is usually a matter of great difficulty to get the arm *w*, or one end of the rock-shaft *s*, at the proper angle to the lever *t*, which can only be generally determined by experiment and after changing the angles a great many times. In order to render this necessary changing of the angles an easy matter, I provide the inner top side of the arm *w* with a conical projection, *w'*, which is provided with teeth, this cone fitting into a corresponding-shaped recess in the cone *s'*, which is rigidly fixed to the rock-shaft at the opposite end of the bearing from the lever *t*. The teeth on the cone *w'* project into the grooves *s*, made in the cone *s'*, when the cone *s'* and cone *w'* are brought together, thus holding the arm *w* at that angle, whatever it may be. By withdrawing the arm *w* slightly, so as to cause the cones to become disengaged, the angle can be readily changed, and when the proper one is determined the arm can be held fast in that position by screwing home the nut *s*, for which the outer end of the rod *s* is adapted, as shown in Fig. 5.

In Fig. 7 is shown my improved device for

securing a perfectly vertical adjustment of the cylinder *a* and mill-frame. This is necessary, as any deviation to any side of the center would bend the pump-rod and give an increased and unnecessary resistance for the wind-wheel to overcome.

The device consists of a central hub or socket, 1, through which passes the lower end of the cylinder *a*, as shown. From the sides of this hub 1 projects the radiating arms or spokes 2, of which there are four, which extend through the rectangular frame *C* placed around the four supporting-posts of the tower. The outer ends of these arms are screw-threaded and are provided with the nuts 3. By means of these nuts the center of the hub carrying the lower end of the cylinder *a* can be readily shifted until a perfectly vertical adjustment of the cylinder is obtained, as will be readily understood.

Having thus described my invention, I claim—

1. The casting or frame *b*, provided with the uprights *b'*, having stops *b*, the lower portion of the casting being rigidly secured to the cylinder *a*, and the top being provided with the circular opening *b*, in which is placed the bushing *c* for the reception of the upper portion of the bracket *d*, substantially as shown.

2. The casting or frame *b*, provided with the uprights *b'*, having stops *b*, the lower portion of the casting being rigidly secured to the cylinder *a*, and the top being provided with the circular opening *b*, in which is placed the bushing *c* for the reception of the upper portion of the bracket *d*, the said bracket *d* being provided with the shaft-bearing *d*, having the projectors *d*, and being further provided with the metallic band or strap *f*, having stops *f*, the lower portion of the bracket being pivoted to the cylinder *a*, whereby the bracket and frame or casting may be turned through a quarter of a circle independently of each other, substantially as set forth.

3. In a windmill, the combination of the cross-head *m* and slot *l*, with the crank-wheel *h*, having pivoted to it the wrist-pin *i*, provided with the nuts *k* and *p* and washer *q*, adapted to be tightened to take up the lost motion as the parts become worn by friction.

4. The rock-shaft *s*, mounted in the bearing *r* and provided with the inside-grooved cone *s'*, in combination with the arm *w*, having the correspondingly-toothed cone or projection *w'*, whereby the shaft and arm may be connected at any desired angle and readily disconnected at will, substantially as described.

5. In a windmill, the combination of the tower *A*, frame *C*, cap *B*, centering device 1, cylinder *a*, frame or casting *b*, rigidly secured thereto and provided with the rearwardly-projecting bracket *g* for carrying the vane *E*, the lower end of said bracket being pivoted to the cylinder *a*, bracket *d*, pivoted at the bottom to the cylinder *a*, between the bracket *g* and frame *b*, and at the top in the bushing *c* in the frame

b, and provided with the band *f*, having stops *f'* and *f''* encircling the casting *b*, wind-wheel *D*, shaft *e*, wheel or crank *h*, wrist-pin *i*, working in the slot *l* in the cross-head *m*, carrying *s* the pump-rod *n*, lever *t*, weight *u*, rock-shaft *s*, arm *w*, and connecting-rod *w'*, all constructed and combined to operate substantially as shown and described.

In testimony whereof I have affixed my signature in presence of two witnesses.

WILLIAM W. HILDRETH.
